UNITED STATES PATENT OFFICE.

ARTHUR W. HEALEY, OF JAMESTOWN, NORTH DAKOTA.

WASHING APPARATUS.

1,240,205.

Specification of Letters Patent. Patented Sept. 18, 1917.

Application filed March 11, 1916, Serial No. 83,622. Renewed July 25, 1917. Serial No. 182,802.

To all whom it may concern:

Be it known that I, ARTHUR W. HEALEY, citizen of the United States, residing at Jamestown, in the county of Stutsman and 5 State of North Dakota, have invented certain new and useful Improvements in Washing Apparatus, of which the following is a specification, reference being had to the accompanying drawings.

10 This invention relates to certain improvements in washing apparatus and it is an object of the invention to provide an apparatus of this general character wherein pressure is imposed upon the articles to be cleansed 15 from opposite sides and wherein the pressure at one side is mechanical and the pressure at the opposite side is afforded by steam pressure.

The invention also has for an object to 20 provide a novel and improved apparatus of this general character including a pounder head mounted for reciprocal movement and coacting with the upper part of the articles to be cleansed, whereby steam is directed upwardly toward the pounder head whereby 25 the cleansing operation is materially facilitated.

It is also an object of the invention to 30 provide a novel and improved apparatus of this general character including a container and mechanical means coacting therewith for operating upon the articles placed within the container and wherein said mechanical means is so mounted as to be moved away 35 from the container so that access may be had therein.

The invention consists in the details of 40 construction and in the combination and arrangement of the several parts of my improved apparatus whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view partly in section and partly in elevation illustrating a washing apparatus constructed in accordance with an 55 embodiment of my invention;

Fig. 2 is a view partly in front elevation and partly in section of the apparatus as herein disclosed;

Fig. 3 is a view in top plan with parts in section of the apparatus as herein set forth, 60 of disclosure;

Fig. 4 is a detail sectional view taken certain of the parts being omitted for clarity substantially on the line 4—4 of Fig. 1;

Fig. 5 is a view partly in elevation and 65 partly in section illustrating an operative connection with one of the pounder heads as herein included; and

Fig. 6 is a view, enlarged, in elevation, 70 illustrating certain details of my invention as herein set forth.

As disclosed in the accompanying drawings, C denotes a container or tub of predetermined dimensions and configuration and in which are adapted to be arranged the 75 pounder heads V to be hereinafter more particularly referred to.

1—1 denote vertically arranged uprights in predetermined spaced relation with which the brackets B are slidably engaged, each 80 of said brackets being substantially in the form of an inverted U and having its stem or long arm 2 slidably engaged with an upright 1 and held by the cross members 3, as is believed to be clearly shown in the 85 accompanying drawings. The stems or vertical arms 2 of the brackets B are tied or connected by the transversely disposed bars 4 whereby it will be perceived that the 90 brackets B will be caused to move in unison and in the same general direction relative to the uprights 1.

The horizontal arms 5 of the brackets B are provided with the upstanding bearings 6 in which are rotatably mounted the crank 95 shafts 7, adjacent ends of said shafts 7 having fixed thereto the gears 8 in mesh with an interposed gear 9 mounted upon a shaft 10 rotatably supported by the horizontal arm 5 of one of the brackets B, said shaft 10 being 100 adapted to be rotated in any desired manner, but more particularly as will be herein-after more fully set forth.

One of the bars 4, preferably the lowermost bar, is provided with the forwardly directed arms 11 in predetermined spaced relation and substantially in parallelism, each of said arms 11 being provided with the vertically directed bearings 12 and through each 105 of said bearings 12 is directed the tubular 110

shank 14 of a pounder head V, said pounder head V being preferably cone shape in form and of a conventional construction.

Telescopically engaged with each of the

5 shanks 14 is a rod 15 provided with the laterally directed finger or pin 16 disposed through a slot 17 arranged longitudinally of the shank 14, whereby it will be perceived that the rod 15 and the shank 14 are capable 10 of limited independent relative movement.

In order to normally maintain the shank 14 in the rod 15 at the limits of their outward movement, I position within the tubular shank 14 below the inner end of the rod 15, 15 the expandible member 18 herein disclosed as a conventional coil spring operating in a manner which is believed to be clearly apparent to those skilled in the art to which my present invention appertains.

20 The outer extremity of the rod 15 has pivotally engaged therewith the pitman 19 which is also operatively engaged with a crank 20 of one of the shafts 7, whereby it will be perceived that upon rotation of a shaft 7, 25 the requisite reciprocation will be imparted to the pounder head V, the stroke of the pounder head being determined by the throw of the crank 20. By having the rod 15 and the tubular shank 14 capable of relative independent movement, it will be perceived 30 that the requisite compression may be had upon the articles within the container or tub C without interfering with the oscillation of the pitman 19.

35 In communication with the interior of the container or tub C through the bottom thereof and directly beneath each of the pounder heads V, is the pipe 21 leading from a suitable source of steam supply independent of the container C and whereby 40 it will be perceived that a continuous upward pressure will be imparted upon the articles to be cleansed from below and in direct alinement with the pressure imparted 45 upon the articles to be cleansed. In addition, the steam serves to cause the cleansing fluid to thoroughly and effectively permeate the articles to be cleansed whereby the cleansing operation is thorough and may be 50 accomplished within a minimum period of time.

As herein disclosed, the shaft 10 herein-before referred to, has affixed to its outer extremity a pulley 22 around which passes 55 a belt 23 which is also directed around a pulley 24 affixed to a shaft 25 operatively supported by the bearings 26 carried by the long arms or stems 2 of the brackets B at a predetermined point intermediate their 60 length, and as herein set forth, said pulley 24 is provided with a crank 27 whereby the shaft 25 may be manually rotated. However, I do not wish to be understood as limiting myself to this particular means for 65 rotating the pulley 24, as the same may be

of a double type as disclosed particularly in Fig. 2, so that an operative connection may be had with any suitable source of power.

The shaft 25 has affixed thereto a clutch 70 member 28 adapted to coact with the clutch face 29 of the drum 30 fixed upon the shaft 25 to rotate therewith, but capable of movement longitudinally thereof so that the clutch face 29 of the drum 30 may be disengaged from the clutch member 28. As herein disclosed, the clutch face 29 of the drum 30 is disengaged from the clutch member 28 by the operating member 31 co-acting with the drum 30 in a conventional 80 manner. It is also to be noted that the clutch face 29 of the drum 30 is automatically moved into engagement with the clutch member 28 by the expandible member 32 herein disclosed as a conventional coil 85 spring interposed between an end of the drum 30 and a bearing 26, as is clearly shown in Fig. 2 of the accompanying drawings.

Suitably secured to the drum 30 and 90 adapted to be wound therearound, is the flexible member 33 which extends upwardly and over a guide pulley 34 suitably supported at a predetermined point above the shafts 7 and then downwardly and operatively engaged, as at 35, with the upper brace bar 4. By this arrangement it will be perceived that when it is desired to apply articles to be cleansed within the container or tub C, or for any other purpose, it is 100 only necessary to permit the clutch face 29 of the drum 30 to interlock with the clutch member 28, whereupon the rotation of the shaft 25 will so wind the flexible member 33 about the drum 30 as to lift or move upwardly the brackets B and thus withdraw the pounder heads V from within the container or tub C a sufficient distance thereabove as to offer no obstruction to the insertion of the articles to be cleansed within the 110 container or tub C or for any other purpose which may be desired. It is also to be understood that after the brackets B have been elevated the desired height, the rotation of the shaft 25 is discontinued. 115

In order to hold the shaft 25 against retrograde movement, which would otherwise permit the pounder heads V to be lowered within the container or tub C, I provide the shaft 25 with a conventional ratchet 120 36 with which coacts a pawl 37 pivotally supported by an adjacent bearing 26, as is particularly illustrated in detail in Fig. 6. In this figure it is to be observed that the dog or pawl 37 is provided with an up-standing tail 38 whereby the pawl or dog 37 may be disengaged from the ratchet 36 when it is desired to return the pounder heads V within the container or tub C. 125

From the foregoing description, it is 130

thought to be obvious that an apparatus constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A washing apparatus comprising a con-

tainer, a plurality of pounder heads mounted for reciprocation in a vertical path relative to and above the bottom of the container, and a pipe coacting with each of the pounder heads and leading from a source of fluid supply under pressure and in communication with the container through the bottom thereof at a point below the axial center of the pounder head, the space between the bottom of the container and the pounder heads being unobstructed.

In testimony whereof I hereunto affix my signature in the presence of two witnesses.

ARTHUR W. HEALEY.

Witnesses:

W. E. LAWSON,
C. M. FORREST.
